CLAIM

The ornamental design for a shoulder bag, as shown and described.

DESCRIPTION

FIG. 1 is an upper front right perspective view of a shoulder bag showing our new design;
FIG. 2 is a front elevational view thereof;
FIG. 3 is a right side elevational view thereof;
FIG. 4 is a rear side elevational view thereof;
FIG. 5 is a left side elevational view thereof;
FIG. 6 is a top view thereof; and,
FIG. 7 is a bottom view thereof.

The broken lines show stitching on the shoulder bag that forms no part of the claimed design.
